H. BRADY AND A. W. HILSINGER,
FEEDING MECHANISM FOR BOX MAKING MACHINES,
APPLICATION FILED AUG. 11, 1916.

1,370,514.

Patented Mar. 8, 1921.

Adm. W. Hilsinger and
Henry Brady, Inventor

By Their Attorney

Thos. J. A. B. H.

UNITED STATES PATENT OFFICE.

HENRY BRADY, OF BLOOMFIELD, AND ADIN W. HILSINGER, OF ORANGE, NEW JERSEY, ASSIGNORS TO HENRY BRADY, INC., A CORPORATION OF NEW JERSEY.

FEEDING MECHANISM FOR BOX-MAKING MACHINES.

1,370,514.

Specification of Letters Patent.

Patented Mar. 8, 1921.

Application filed August 11, 1916. Serial No. 114,352.

To all whom it may concern:

Be it known that I, HENRY BRADY, a citizen of the United States, and residing at Bloomfield, county of Essex, State of New Jersey, and I, ADIN W. HILSINGER, a citizen of the United States, residing at Orange, county of Essex, State of New Jersey, have invented certain new and useful Improvements in Feeding Mechanism for Box-Making Machines, of which the following is a specification, reference being had therein to the accompanying drawing.

Our invention relates to improvements in box making machinery and more particularly has reference to feeding mechanism adapted for feeding paper, card board or similar material from which the boxes are to be made into the machine and is an improvement on the feeding mechanism in co-pending patent application to Henry Brady, Serial No. 337,302, filed Nov. 11, 1919.

Referring to the accompanying drawing marked Figure 1 we have illustrated therein in perspective view with parts broken away an application of our invention. 2 indicates a suitable base or support upon which the standards 3—4 are mounted and likewise the standards 5—6. The standards first mentioned are adapted to support the frame work 7 within which the shaft 8 is mounted and upon which is secured the pulley 9, adapted to be driven by a belt such as 10 or other suitable means. The end of the driven shaft 8 is also provided with a pinion such as 11 which meshes with the pinion or gear 12 upon the shaft 13 which is provided at the opposite extremity with a sprocket 14, provided with the sprocket chain 15 which in turn passes over the sprocket 16 upon the shaft 17, also secured upon the standards 3—4. Said shaft 17 is also provided with a pulley 18 which drives the belt 19 over the pulley 20, said last mentioned pulley being mounted in the end of the bar 21 which has an extension or projection 22 and rests upon the shaft 17 allowing said shaft to freely rotate thereon and it is provided with a weight such as 23 which serves to keep the pulley 20 and its belt 19 against the periphery of the roll of paper or board 24 mounted upon the shaft 25 in the top of the standards 5—6.

From the foregoing it will be readily understood that as the pulley 9 is driven by

the belt 10 the pinion 11 upon the same 55 shaft, drives the pinion 12 and the sprocket 14 upon said shaft. This in turn drives the shaft 17 through the sprocket 16, and the belt thereby travels in the direction of the arrow against the peripheral face of the 60 paper roll 24, thus causing the same to feed leftly in the machine as indicated by the arrow at the top to the rolls 26—27 and the roll 26 is mounted upon a suitable shaft or spindle as shown. 28 is a pinion which 65 meshes with the rack 29 which is pivotally connected at 30 to the lever 31 upon the shaft 13 so that as said shaft 13 rotates, the rack 29 serving as a connecting rod reciprocates and its teeth being in engagement with the pinion 28 cause the same to rotate first 70 in one direction and then in the other. Suitable ratchet mechanism not shown is provided so as to cause the pinion 28 to rotate the shaft or spindle of the roll 26 when 75 turning in one direction only, thus being free to move in the reverse direction. Such mechanism is shown in copending patent application referred to, and as such mechanisms are well known it is not deemed necessary to make further disclosure herein. The result is that the paper is fed intermittently 80 in the same direction in the machine, thus allowing the same to be cut off in predetermined lengths and to be folded and finished 85 in any desirable manner thereafter.

32—33 indicate suitable fingers or guides for engaging the opposite edges of the paper for controlling the same as it enters the machine.

Of course it will be understood that various modifications may be made in the construction and arrangement of parts without departing from the spirit of the invention as claimed.

We claim:

1. In a machine of the class described, a supply roll and a mechanism for controlling the slack of the web as it is fed therefrom, said mechanism comprising an endless belt 100 adapted to be driven against the periphery of said roll, and means for adjusting the tension of said belt whereby the slack in said web may be regulated.

2. In a machine of the class described, a supply roll and a mechanism for controlling the slack of the web as it is fed therefrom, said mechanism comprising an endless belt 105

adapted to be driven against the periphery of said roll, and means for adjusting the tension of said belt whereby the slack in said web may be regulated, said tension adjusting means comprising a pivoted counter-weight for controlling the pressure of said belt upon said roll.

In testimony whereof we hereunto affix

our signatures in the presence of two witnesses.

HENRY BRADY.
ADIN W. HILSINGER.

Witnesses:

ROY M. MERSHON,
H. M. SUPPEY.
